UNITED STATES PATENT OFFICE.

JOSEPH EDWARD JOHNSON, OF MERIDEN, CONNECTICUT.

CASTER.

No. 909,305.

Specification of Letters Patent.

Patented Jan. 12, 1909.

Application filed September 12, 1908. Serial No. 452,793.

To all whom it may concern:

Be it known that I, JOSEPH E. JOHNSON, a citizen of the United States, residing at Meriden, in the county of New Haven and State of Connecticut, have invented a new and useful Improvement in Casters; and I do hereby declare the following, when taken in connection with the accompanying drawings and the letters of reference marked thereon, to be a full, clear, and exact description of the same, and which said drawings constitute part of this specification, and represent, in—

Figure 1 a side view of a caster constructed in accordance with my invention. Fig. 2 a side view of the tubular portion of the socket, detached. Fig. 3 a side view of the spring, detached. Fig. 4 a sectional view of the socket showing the pintle therein on an enlarged scale. Fig. 5 a sectional view of a modified form of securing the spring in the socket. Fig. 6 a sectional view showing the socket frictionally engaged with the spring.

This invention relates to an improvement in casters and particularly to that class in which the caster proper is provided with a pintle adapted to enter and be retained in a tubular socket entered into the leg of furniture, and are sometimes called furniture casters.

The object of this invention is to provide means for holding the pintle in the socket by means of springs arranged within the socket but independent of the socket, so that the strain of the pintle in the socket does not affect the spring; and the invention consists in the construction hereinafter described and particularly recited in the claims.

The caster comprises a wheel 2, horn 3 and pintle 4 of usual construction, the pintle having the usual head 5 which is larger in diameter than the body portion of the pintle so as to form a shoulder 6. The socket member comprises the usual track plate 7 and a tubular member 8 which may be formed from a single piece of metal folded together or drawn, and at its open end is interlocked with the track plate usually by forming a rib 9 above the track plate and a rib 10 below the track plate, the ribs being closed together upon the edge of the central opening in the track plate. This socket corresponds in length to the length of the pintle and so that the upper end of the socket rests upon the top, or bottom, of the pintle, or both at the same time, and hence forms

bearing points. Within the socket I arrange a spring 11. This may be of tubular form cut from spring metal and formed at its upper end with notches 12 more or less in number, to form spring fingers 13. At its lower end it is formed with a flange 14 adapted to be interlocked with the socket either above or below the track plate. As shown in Fig. 4 of the drawings, it is interlocked below the track plate, and as shown in Fig. 5 of the drawings it is interlocked above the track plate; and this spring, while preferably formed from a single piece, might clearly be formed from separate pieces which together form substantially a tube. The length of this spring is such as to extend into the socket to such a distance as to allow the head of the pintle to pass beyond it, the spring arms 13 entering below the shoulder 6. If the spring is made from a tubular piece, its lower end may be interlocked with the track plate and the socket set over the top of the spring and have its lower end engage frictionally with the spring so as to be held in place or the socket may be welded to spring as shown in Fig. 6. While this spring yields to permit the pintle to be entered into the socket, when it is entered into the socket, the head 5 extending above the springs 13 cannot readily be withdrawn, although it may be when sufficient force is applied. The pintle bearing against the top of the socket above the springs or at the bottom or both, does not affect the springs when the pintle is turned under strain. As shown the upper end of the socket will be slightly tapered to facilitate the entrance of it into the hole provided for it in furniture legs.

I claim:

1. The herein described socket for casters comprising a tubular member, a tubular spring arranged within said tubular member permanently connected at its lower end with said tubular member and extending upward to a point below the upper end of the tubular member, substantially as described.

2. A caster comprising a tubular socket closed at its upper end, a tubular spring member coupled at its lower end therewith and extending upward into the socket, said spring member slotted at its upper end, and the metal between the slots turned inward, substantially as described.

3. A caster comprising a pintle having a

head at its upper end, of a socket, a track plate with which the socket is engaged, a tubular spring member within said socket, said tubular spring member interlocked at its lower end with the socket and terminating at a point below the upper end of the socket, substantially as described.

In testimony whereof, I have signed this specification in the presence of two subscribing witnesses.

JOSEPH EDWARD JOHNSON.
